ULRICH KORNSTEIN, OF NEW YORK, N. Y.

HAIR-DRYING COMB.

1,329,301.

Specification of Letters Patent. Patented Jan. 27, 1920.

Application filed March 20, 1919. Serial No. 283,900.

To all whom it may concern:

Be it known that I, ULRICH KORNSTEIN, a citizen of the United States, and a resident of New York, in the county of New York and State of New York, have invented certain new and useful Improvements in Hair-Drying Combs, of which the following is a specification.

The present invention relates to improvements in hair-drying combs, and has for one of its objects to provide an implement of this type wherein the hollow back of the comb is rigidly secured to the handle, suitable reinforcing means being provided for preventing a deformation of the said back.

Another object of the invention is to provide an implement of the character specified which is simple in construction, durable, efficient in operation, and which can be manufactured on a commercial scale or, in other words, one which is not so difficult to produce as to be beyond the reasonable cost of such an article.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

One of the many possible embodiments of the invention is illustrated in the accompanying drawings, in which:—

Figure 1 is a longitudinal central section taken through a comb constructed in accordance with the present invention; and Fig. 2 is a section taken on line 2—2 of Fig. 1.

In the drawings, the numeral 10 indicates the comb portion of the implement. This comb portion is formed of a heat-conducting material, such as metal, and comprises the usual teeth 11 and a hollow back 12. The teeth and back are, preferably, made of one integral piece, the hollow back being formed by bending the material of the body of the comb beyond the teeth into tubular shape, as clearly shown in Fig. 2 of the drawings.

One end of the back, denoted by the numeral 13, extends beyond the body portion of the

comb and is inserted into a bore 14 of a handle 15. This handle is, preferably, of wood or other non-conductor of heat, so that the hand of the operator will not be burned in using the comb. Beyond the portion 13 of the back the bore 14 is reduced to a diameter that corresponds to the inner diameter of the back of the comb, a reinforcing, preferably metallic, rod 16 being inserted into the reduced portion of the said bore, said rod also projecting a substantial distance beyond the handle into the said back.

Over the inner end of the handle 15 is drawn a ferrule 17, said ferrule, comb, handle and reinforcing rod being united by a pin 18, passing through these four elements. The portion of the reinforcing rod that is disposed within the reduced portion of the bore 14 may be suitably roughened, as shown at 19, for a purpose hereinafter to be described.

Adjacent the ferrule the body portion of the comb is notched, as shown at 20, the configuration of the said notch corresponding to the curvature of the outer end of the ferrule, whereby the comb body is adapted to abut against the ferrule, as clearly shown in Fig. 1 of the drawings.

A heating rod or core 21 of a slightly smaller diameter than the inner diameter of the comb back is provided. One end of this rod is reduced in diameter, as clearly shown at 22, and inserted into a bore 23 in a handle 24, of wood or other non-conductor of heat, so that the heating rod may be handled without danger of burning the hand of the operator. Within the bore 23 is disposed a sleeve 25 of asbestos or similar material, said sleeve covering the reduced end 22 of the core 21. A pin 26 passes through the handle 24 and the core 21, to properly unite these two elements.

When the comb is to be used for heating, the core 21 is heated to a sufficient degree necessary for the purpose, and is then placed within the hollow back of the comb. The heat of the core is transmitted to the comb, which is thus ready for use as a drier or as a hair curler.

In assembling the comb, first the ferrule 17 is placed upon the handle 15, and then the reinforcing member 16 forced into the bore thereof, the roughened portions 19 of the said reinforcing member holding the latter in place. The end 13 of the back of the

comb is then put in place, after which a hole is drilled through the four elements mentioned, and into the said hole is driven the pin 18. The reinforcing member 16, projecting into the back of the comb, prevents the latter from being twisted, as is usually the case with the constructions heretofore in use. The notch 20 in the body of the comb allows the said body to be brought as close as possible to the ferrule, thus giving the said body a support in the form of an abutment.

What I claim is:—

1. In a hair-drying comb, the combination with a comb having a hollow back, of a handle having a bore in which a portion of said hollow back is seated, a reinforcing bar in the bore of said handle, said bar projecting into said back a substantial distance be-

yond said handle, and fastening means passing through said handle, back and reinforcing bar. 20

2. In a hair drying comb, the combination with a comb having a hollow back, of a handle having a bore in which a portion of 25 said hollow back is seated, a ferrule on said handle, a reinforcing bar in the bore of said handle, said bar projecting into said back a substantial distance beyond said ferrule, and fastening means passing through said handle, ferrule, back and reinforcing bar, the body portion of said comb being provided with a notch into which part of said ferrule snugly fits. 30

Signed at New York, in the county of 35 New York, and State of New York, this 14th day of March, A. D. 1919

ULRICH KORNSTEIN.
